UNITED STATES PATENT OFFICE

163,928

HELICOPTER

Charles Arthur Barnett, Lansdale, Pa., assignor
to Kellett Aircraft Corporation, a corporation
of Delaware

Application August 26, 1950, Serial No. 11,941

Term of patent 14 years

(Cl. D71—1)

To all whom it may concern:

Be it known that I, Charles Arthur Barnett, a citizen of the United States, residing at Lansdale, in the county of Montgomery, and State of Pennsylvania, have invented a new, original, and ornamental Design for a Helicopter, of which the following is a specification, reference being had to the accompanying drawings, forming a part hereof.

Fig. 1 is a front perspective view of the helicopter embodying the new design;

Fig. 2 is a plan view;

Fig. 3 is a front elevational view; and

Fig. 4 is a rear elevational view thereof.

The appearance of the opposite side of the helicopter is substantially similar to that shown in Fig. 1.

I claim:

The ornamental design for a helicopter, substantially as shown and described.

CHARLES ARTHUR BARNETT.
